[57] CLAIM

The ornamental design for a watch band, as shown and described.

DESCRIPTION

FIG. 1 is a perspective view of a watch band showing my new design;

FIG. 2 is a top plan view;

FIG. 3 is a side elevational view; the opposite side view being a mirror image;

FIG. 4 is a front elevational view;

FIG. 5 is a rear elevational view; and,

FIG. 6 is a bottom plan view.

The broken line showing of a watch in FIG. 1 and a clasp in FIGS. 1 through 6 is for illustrative purposes only and forms no part of the claimed design.
